[57] CLAIM

The ornamental design for a combined pendulum game and score display screen therefor, as shown and described.

DESCRIPTION

FIG. 1 is a perspective view of a combined pendulum game and score display screen therefor showing my new design;

FIG. 2 is a top plan view thereof;

FIG. 3 is a bottom plan view thereof;

FIG. 4 is a right side elevational view of the score display screen member;

FIG. 5 is a left side elevational view thereof;

FIG. 6 is an end elevational view thereof;

FIG. 7 is an end elevational view of the end opposite that shown in FIG. 6; and,

FIG. 8 is a side elevational view of the finger band member.

The broken line showing of a human hand in FIG. 1 shows environment only and forms no part of the claimed design.
